UNITED STATES PATENT OFFICE.

FRANK A. POWERS AND THOMAS KLIPFEL, OF CHICAGO, ILLINOIS, ASSIGNEES TO UNION WIRE MATTRESS COMPANY, OF CHICAGO, ILLINOIS, A CORPORATION OF ILLINOIS.

BED-BOTTOM.

No. 872,681.

Specification of Letters Patent.

Patented Dec. 3, 1907.

Application filed April 27, 1907. Serial No. 370,722.

To all whom it may concern:

Be it known that we, FRANK A. POWERS and THOMAS KLIPFEL, citizens of the United States, and residents of Chicago, in the county of Cook and State of Illinois, have invented certain new and useful Improvements in Bed-Bottoms, of which the following is a specification.

This invention relates to bed bottoms of 10 that general type which comprises a wire fabric made up of interhooked bent-wire units or links connected at its ends to the head and foot rails of the frame by transverse rows of helicals designed to afford the requisite elasticity.

The leading object of the invention is to provide a bed bottom of this character which shall possess the requisite elastic or 20 spring quality as an entirety, but wherein local bending and sagging effects shall be reduced to a minimum.

A minor object is to provide a structure well adapted to preserve, under load, the true relative positions of the various units 25 and links composing the same.

These objects we accomplish through a construction wherein local strains are to a considerable extent distributed throughout the entire fabric, and wherein the several longitudinal strands of which the fabric is composed are so connected laterally as to preserve their substantial parallelism under load.

Our invention will be readily understood when considered in connection with the accompanying drawings, which show an approved mechanical embodiment thereof, and in which,—

Figure 1 is a top plan view of our improved bed bottom applied to the bed bottom frame. 40 Fig. 2 is a fragmentary view of one corner portion of Fig. 1 on a considerably enlarged scale for the sake of greater clearness of detail. Fig. 3 is an edge view of Fig. 2.

Referring to the drawings, 5 and 6 may designate the head and foot rails, respectively, 7 the parallel side rails, and 8 the connecting corner brackets of the bed frame; these latter being connected to the vertical members of the angle iron end rails 5 and 6 by the bolts 50 9 and nuts 10 (Fig. 3) in a manner well understood. The head and foot rails 5 and 6 are apertured at intervals, as usual, to receive the usual end rows of helical springs 11 and 12, respectively.

55 The main body of the fabric constituting

the covering of the bed bottom is made up by a plurality of parallel longitudinal rows of U-shaped bent-wire units 13; the individual units of each row being connected by forming hooks 14 on the free ends of the side members 60 of the units, which hooks are engaged with the closed ends of adjacent units. This form of unit and mode of connection is known among manufacturers of this type of bed bottom, and no invention in the specific form of 65 such unit is herein claimed by us. The fabric is connected at one end to the adjacent row of helicals 11 by spreading the side members of the end row of units so as to cause adjacent side members 13^a of laterally adjacent 70 units to interhook with a helical disposed midway therebetween, as clearly shown in the detail view, Fig. 2. At the other end of the fabric connection is conveniently made to the helicals through the interposition of 75 V-shaped links 15 engaging the helicals at their closed ends and at their open ends hooking into adjacent units of laterally adjacent strands. The helicals place the entire fabric under considerable tension so as to 80 give a smooth, uniform and practically level surface to the fabric as a whole.

Heretofore, so far as we are aware, in fabrics of this type the parallel longitudinal strands have been commonly connected laterally by independent transverse links flexibly connected to the units. This construction, while permitting of a lengthwise as well as a crosswise folding of the fabric for shipment or storage, has but slight mechanical 90 value in the direction of a lateral distribution of the strains between the several longitudinal strands.

One object of our present invention, as already suggested, is to minimize local bowing 95 or sagging effects, especially in a direction crosswise of the fabric; and this object we attain by the following means. 16 designates each of a pair of side wires that are somewhat heavier than the wire of which the 100 units of the fabric are composed, which side wires are connected to and between the ends of the head and foot rails by means of helicals 17 that are preferably somewhat longer than the intermediate helicals 11 and 12. Extending between and supported by said side wires at suitably spaced intervals in a manner to form transverse supports for the fabric are a series of cross wires 18. Preferably these wires are passed through the down- 110

wardly turned hooks 14 of those transverse rows of units which they underlie, this arrangement tending to maintain the proper tensioning and uniform spacing of the cross wires. Surrounding the cross wires 18 between adjacent longitudinal rows of units are spacing sleeves or ferrules 19. These latter may be solid as indicated in Fig. 1, or they may be cheaply made of wire closely coiled on a mandrel, as shown at 19^a in Figs. 2 and 3. It will be seen that by reason of this construction, the bending strains received by the several individual longitudinal strands are transmitted and distributed in a considerable measure to and throughout adjacent strands, while the strains received by the fabric as a whole are to a considerable extent transmitted through the cross wires 18 to the heavier side wires 16. The result of this construction is that, while the bed bottom as a whole is of a springy and resilient character, yet excessive local bending and sagging is done away with; spreading of the longitudinal strands is prevented; and the fabric readily regains and retains its substantially level form throughout when relieved of load.

It will be evident that our invention is capable of being carried out with other forms of bent-wire units than those herein shown, and also that the supporting cross wires might be otherwise connected to the longitudinal strands or caused to merely underlie the latter. The specific forms of spacing sleeves shown are also not of the essence of the invention in its broader aspects.

Other changes in the details of the structure might likewise be made by those skilled in the art without departing from the principle or sacrificing any of the advantages of the invention.

We claim:

1. A bed bottom comprising a frame, a bed bottom fabric, end rows of helicals connecting said fabric to the head and foot rails of said frame, side wires connecting the ends of said head and foot rails, and cross wires connecting said side wires at intervals and supporting said fabric, substantially as described.
2. A bed bottom comprising a frame, a bed

bottom fabric composed of parallel longitudinal strands of interhooked units, end rows of helicals connecting said fabric to the head and foot rails of said frame, side wires connecting the ends of said head and foot rails, and cross wires connecting said side wires at intervals and passed through the hooks of transverse rows of units in said fabric, substantially as described. 55

3. A bed bottom comprising a frame, a bed bottom fabric composed of parallel longitudinal strands of bent-wire units, end rows of helicals connecting said fabric to the head and foot rails of said frame, side wires connecting the ends of said head and foot rails, cross wires connecting said side wires at intervals and supporting said fabric, and spacing sleeves on said side wires between adjacent longitudinal rows of units in said fabric, 60 substantially as described. 65

4. A bed bottom comprising a frame, a bed bottom fabric composed of parallel longitudinal strands of interhooked bent-wire units, end rows of helicals connecting said fabric to the head and foot rails of said frame, side wires connecting the ends of said head and foot rails, cross wires connecting said side wires at intervals and passed through the hooks of transverse rows of units in said fabric, 75 and spacing sleeves on said side wires between adjacent longitudinal rows of units in said fabric, substantially as described. 80

5. A bed bottom comprising a frame, a bed bottom fabric composed of parallel longitudinal strands of interhooked bent-wire units, side wires disposed alongside the opposite edges of said fabric, end rows of helicals connecting said fabric and said side wires to the head and foot rails of said frame, cross wires 85 connecting said side wires at intervals and passed through the hooks of transverse rows of units in said fabric, and spacing sleeves on said wires between adjacent longitudinal rows of units in said fabric, substantially as 90 described. 95
